CRUDE OIL BURNER

Arien Dekker, Fynaart, Netherlands

Application March 24, 1948, Serial No. 19,842

3 Claims. (Cl. 158—91)

1

This invention relates to crude-oil burners, especially for ranges, stoves, furnaces, water heaters and other domestic appliances of the type that will be operated by natural draft without the use of motors and other moving parts, and is an improvement upon the burner shown and described in my Patent No. 2,367,460.

An object of the invention is to provide an efficient and compact structure, that may be manufactured and used economically. A further object is to provide a burner of this type that will not be liable to be choked up by a deposit in consequence of bad combustion.

Other objects will become apparent as the invention is more fully set forth.

In order to illustrate an embodiment of this invention, reference is made to the following description and the appended drawings in which:

Fig. I is a vertical section of the burner, Fig. II a view of the slots in the air regulator, Fig. III a view of the overflow of the evaporation pan.

The present burner has an ascending inclination of the oil-gas outlet slit 3 lying between an inclined baffle plate fixed to or united with the wall 10 of the burner and an inclined part of the bottom of the cover 8. Said gas outlet slit communicates with a vertical annular space between the wall 10 and the cover 8 but as the cover 8 of the evaporation pan 1 gets a higher temperature than said pan it expands more and closes the vertical annular space when used in burners with a bigger diameter and when burning at full load so that the gas cannot flow through said slit and dangerous pressures may be built up in the covered annular vaporizing pan 1. The inclined part of the bottom of the cover 8 has ribs 43 at its underside supporting said cover upon the baffle plate by which the narrowing or closing of the gas-outlet slit 3 is prevented. Since the vertical annular space does not serve as a gas-outlet slit as in the patent referred to, said annular space may have such dimensions that it can never be closed. The lower pan or residue combustion chamber 17 has a hollow upstanding column 18 on its bottom communicating through an opening in said bottom and through a hole 19 in the protection base 20 with the atmosphere so that combustion air enters into the column 18 from where it passes through the holes 34 into an annular space 9 confined by said hollow column 18 and a cylindrical extension of the cover so that flames are formed at the apertures burning clean said cylindrical extension of the cover and thereby preventing the choking up of said annular space.

2

The wall 10 may have a band 12 with sloping slots 13 and pins 14 for moving the band up and downwards and closing or opening air holes 11 so that all rows of air holes 11 are open when an associated cock is full open and one or more rows of holes are closed when the cock is nearly closed. The overflow 22 of the evaporation pan 1 is connected with the oil supply pipe before the oil-lock 21 whereby air is prevented from flowing into the pan through its overflow. The gas-outlet slit 3 may be provided with ribs 43 thereby compelling the gas to pass through slots between said ribs. The residue outlet consists of a hole 5 in a bottom part of the evaporating pan. The underside of said part around said hole 5 tapers downwards and upwards to the edge of said hole from all sides so that combustion air through an air inlet 25 may reach the surface of the bottom behind said hole thereby avoiding the formation 20 of coke behind said hole and its choking up.

The operation of the burner is substantially as follows:

The burner is pressed by means of a suitable support against the flame inlet pipe 41 of the 25 cooking range, stove or geyser or the like, which is connected with a chimney.

The pan 1 is raised from the lower pan 17 by turning the handle 29 of the protection base 20 connected with the pan 17 which has slanting 30 notches in which slanting cams at the bottom of pan 1 slide thereby lifting pan 1 from pan 17 and obtaining sufficient space to throw a burning match into the thin layer of oil, which has flowed through the oil pipe 23, the oil lock 21, the hole 33, the pan 1 and the residue hole 5 onto the bottom of the lower pan 17. The flame rises through the hole 9 between the gasifying pan and the column 18 heating the bottom 2 of the pan 1 and its cover 8 with the ribs 35 and the column 40 18 on its way to the appliance which is to be heated.

The column 18 transmits its heat to the bottom of the lower pan 17 causing such a rapid production of gas that gas flames pass outside the burner 45 and back into the gas combustion chamber 6 through the holes 11 and heat the wall 10 of the pan 1, the ribs 36 and the surface 37 of the cover 8. Soon the gasification of the oil in the pan 1 becomes so great that the gas escapes through the 50 gas-outlet slit 3 and is ignited by the flame from the residue combustion chamber 7. In the meantime this flame has begun to heat the appliance. The gas flame, which is the hot-economical flame and the principal one, touches the ribs 36 and the upper surface 37 of the cover 8, obtaining its combustion air through the holes 11. Soon the gasi-

fying reaches its maximum and very little residue passes through the hole 5 into the residue combustion chamber 7. When flames no longer pass to the outside from the residue combustion chamber 7, the handle 29 is turned back and the pan 1 again fits close on the lower pan 17, combustion air passing only through the small slots 25.

The inclining gas-outlet slit enables deposits in the slit to flow into the pan 1 thereby preventing choking up of said slit like the vertical slit does.

I claim:

1. In a crude oil burner with two separate combustion chambers, one for burning the oil-gas from a vaporizing pan and another for burning the residue, the heavy non-vaporized parts of the oil, and for heating said vaporizing pan in order to maintain the vaporizing of the oil in said pan, when heavier oils than kerosene are used, the combination of an annular vaporizing pan, which has a sloping bottom and is closed by an annular cover except for an oil-gas outlet communicating with an oil-gas combustion chamber above the cover of the vaporizing pan, said chamber being provided with holes in its wall for the supply of combustion air, an oil-supply at the top of the sloping bottom of the vaporizing pan, a residue outlet opening in the lowest part of said bottom, a separate residue combustion chamber under said residue outlet opening and concentrically with the vaporizing pan, which chamber has holes in its wall for the supply of combustion air for burning the residue, the flame of which heats the pan and its cover, a few rows of air holes opposite the inner walls of the vaporizing pan and its cover, said holes being situated in the wall of a hollow column on the bottom of the residue combustion chamber, the top of said column being substantially closed and the bottom communicating with the atmosphere whereby small flames are formed at the end of said holes, which flames touch said innerwalls, burn them clean and prevent the formation of deposit on said walls thereby eliminating the choking up of the annular hole formed by said inner walls and the column, said hole being the communication of the separate residue combustion chamber with the chimney.

2. In a crude oil burner with two separate combustion chambers, one for burning the oil-gas from a vaporizing pan and another for burning the residue, the heavy non-evaporated parts of the oil, and for heating said vaporizing pan in order to maintain the vaporizing of the oil in said pan, when heavier oils than kerosene are used, the combination of an annular vaporizing pan, which has a sloping bottom and is closed by an annular cover except for a slit-shaped oil-

gas outlet communicating with a vertical annular space formed by the outer wall of said annular cover and the wall of the burner, said annular vertical space communicating with an oil-gas combustion chamber above the cover of the vaporizing pan, said slit-shaped outlet having an ascending inclination and ribs at one of its walls and inside the slit so that it never can be closed or nearly closed by expansion of the annular cover, said vertical annular space communicating with an oil-gas combustion chamber above the cover of the vaporizing pan, said chamber being provided with holes in its wall for the supply of combustion air, an oil-supply at the top of the sloping bottom of the vaporizing pan, a residue outlet opening in the lowest part of said bottom, a separate residue combustion chamber under said residue outlet opening and concentrically with the vaporizing pan, which chamber has holes in its wall for the supply of combustion air for burning the residue, the flame of which heats the pan and its cover.

3. In a crude oil burner with two separate combustion chambers one for burning the oil-gas from a vaporizing pan and another for burning the residue, the heavy non-vaporized parts of the oil, and for heating said vaporizing pan in order to maintain the vaporizing of the oil in said pan, when heavier oils than kerosene are used, the combination of an annular vaporizing pan, which has a sloping bottom and is closed by an annular cover except for a slit-shaped oil-gas outlet communicating with an oil-gas combustion chamber above the cover of the vaporizing pan, said chamber being provided with holes in its wall for the supply of combustion air, an oil supply at the top of the sloping bottom of the vaporizing pan, a residue outlet opening in the lowest part of said bottom, the underside of said bottom around said residue opening tapering downwards and towards the edge of said opening from all sides, a separate residue combustion chamber under the residue outlet opening and concentrically with the vaporizing pan, which chamber has holes in its wall for the supply of combustion air for burning the residue, the flame of which heats the pan and its cover.
